UNITED STATES PATENT OFFICE

ROBERT C. LUNSFORD, JR., OF HOUSTON, TEXAS, ASSIGNOR TO HUGHES TOOL COMPANY, OF HOUSTON, TEXAS, A CORPORATION OF TEXAS

MOUNTING FOR ACID BOTTLES

Application filed November 25, 1930. Serial No. 497,982.

This invention relates to a supporting structure for acid bottles used as inclination detectors in rotary well drilling.

It is an object of the invention to provide an annular type of container for corrosive or marking liquid which may be supported in a tubular mounting.

A further object is to provide an acid bottle support in tool joints such as are commonly used in connecting the sections of drill stem together, in which the said bottle can be easily inserted and withdrawn.

The aim of the invention is to provide an acid bottle in which a record can be accurately made and which can be conveniently housed and supported.

Referring to the drawing, a central longitudinal section through a tool joint is shown, equipped with the invention.

20 The tool joint is made up of the usual pin member 1, having a socket 2, threaded to receive the threaded end of a drill pipe section, not shown. The lower end is reduced in diameter to provide a shoulder 3, and has 25 a tapered pin 4, threaded with a coarse thread to engage within the socket or box 5, of the box member 6 of the tool joint.

The box member 6 also has a threaded pipe-receiving socket 7 to connect with the drill pipe. The two sections of the tool joint have a fluid passage 8 therethrough of comparatively small internal diameter to allow for strength in the stock of the joint. The box member has the passage recessed below the 35 threaded box 5 as shown at 9 to receive the acid bottle 10.

The said acid bottle is annular in shape, and of the proper internal and external diameter to fit within the recess 9 and not obstruct the passage 8. The bottle may be of any desired material designed to be etched or marked by the marking liquid to be placed therein. Said bottle may rest upon a spring washer or plate 11 at the bottom of the recess 9 and having upwardly bent tongues 12 thereon to resiliently support the bottle.

The bottle is adapted to be closed by an annular nut 13, threaded to screw into the walls of the recess and below the tapered box 5. Said nut has a downward projection

14 adapted to engage within the upper end of the bottle, and displace some of the liquid therein.

To protect the inner face of the bottle, a thin ring 15 of hard metal is used as a wall 55 about the inner side of the recess 9. This wall may be secured to the nut by welding as at 16, and thus constitute a skirt which protects the bottle and closes the recess.

In use the bottle is assembled in the recess 60 9 as shown, the bottle is partly filled with corrosive or marking liquid adapted to make a line upon the bottle. The rest of the bottle is filled with a light gravity liquid, such as oil or gasoline adapted to float upon the 65 acid. When the nut is then screwed in place it will displace some of the light liquid into the recess 9 and close the upper end of the bottle thus acting to prevent splashing the marking liquid in use. The tool joint will 70 be connected into the drill stem line and will be affected by inclination from the vertical and will mark a line indicating the level of the marking liquid. When the drill is withdrawn from the well, the line marked 75 on the bottle by the marking liquid may be noted to learn the inclination of the drill stem.

The use of the annular form of bottle makes it possible to obtain a more accurate 80 record and also enables the bottle to be used in tool joints as described where it may be easily accessible.

What is claimed as new is:—

1. An acid bottle for inclinometers comprising an annular container adapted to surround a tubular passage, and means to close the upper end of said bottle, acting also to fix said bottle in position.

2. An acid bottle for inclinometers comprising an annular container adapted to surround a tubular passage, a plug to close the upper end of said bottle, acting also to fix said bottle in position and an annular projection on said plug acting also to displace some of 95 the liquid in said bottle.

3. The combination of a tool joint having a central passage therethrough and a recess about said passage with an acid bottle of annular shape in said recess, and a plug thread- 100

ed in said recess and acting to close said bottle.

4. The combination of a tool joint having a central passage therethrough and a recess about said passage with an acid bottle of an-
5 nular shape in said recess, and resilient means to support said bottle, and a plug threaded in said recess and acting to close said bottle.

5. The combination of a tool joint having 10 a central passage therethrough and a recess about said passage with an acid bottle of an-
nular shape in said recess, and a plug threaded in said recess and acting to close said bot-
tle, said plug having a skirt thereon to pro-
15 tect said bottle.

6. A tool joint including box and pin mem-
bers, a recess between said members, an an-
nular bottle in said recess, an annular nut
threaded to engage in said recess and close
20 said said bottle, and an annular projection
on said nut to engage within the upper end
of said bottle.

In testimony whereof, I hereunto affix my
signature this 31st day of October A. D.
25 1930.
